UNITED STATES PATENT OFFICE.

THOMAS S. NEWMAN, OF NEWTON, MASSACHUSETTS.

GAS-LIGHTING DEVICE.

1,045,874.

Specification of Letters Patent. Patented Dec. 3, 1912.

Application filed July 18, 1912. Serial No. 710,157.

To all whom it may concern:

Be it known that I, THOMAS S. NEWMAN, a citizen of the United States, residing at Newton, in the county of Middlesex and 5 State of Massachusetts, have invented new and useful Improvements in Gas-Lighting Devices, of which the following is a specification.

This invention relates to improvements in 10 gas lighting devices and particularly to those devices designed to light a plurality of jets by means of a lighted torch connected with a gas supply.

This invention is especially adapted to be 15 used in connection with an ordinary gas stove having a plurality of burners on or near its upper surface.

The device of this invention can be easily 20 built into gas stoves when the same are being constructed and it has the further advantage of being very easily attached to a great many types of gas stoves already in actual use.

My invention has for its object the 25 provisions of a simple and effective appliance for quickly and safely lighting a plurality of burners of a gas stove, said appliance being not only effective but cheap, both in regard to its initial cost and the after expense 30 of operation.

Another object of my invention is to provide a device of the character indicated in 35 which all of the working parts are exposed to view and manipulation so that the same can be easily kept in repair or replaced if broken—the same idea as prevails in the modern “open plumbing.”

The invention consists in the combination 40 and arrangement of parts set forth in the following specification and particularly pointed out in the claims.

Referring to the drawings Figure 1 is a 45 plan view of an ordinary gas stove with my gas lighting device attached thereto, showing a portion of the top of the stove broken away. Fig. 2 is a side elevation of the device. Fig. 3 is a detail cross section of a portion of my device illustrating a portion 50 of the supply pipe, torch and the pipe connecting said supply pipe and said torch.

Like numerals refer to like parts throughout the several views of the drawings.

In the drawings 4 is a gas stove provided 55 with burners or jets 5, 6, 7 and 8. These burners are supplied with gas from the main supply pipe 9 which is located along the

front top edge of the stove. The supply pipe 10 on my device is connected with the main supply pipe 9 and projects inwardly therefrom. Fixed to the supply pipe 10 are 60 the brackets 11 and 12. Rotatably mounted in said brackets 11 and 12 is an operating rod 13 which is provided at its outer end with a handle 14 and at its inner end with a gear 15. At the inner end of the supply 65 pipe 10 is an upwardly projecting elbow 16. Fixed to and connected with this elbow is a connecting pipe 17. Rotatably mounted on and connected with the connecting pipe 17 is a torch 18 which has an upwardly projecting portion 19 and a horizontally projecting portion 20. The bore 21 of the connecting pipe 17 is much smaller in diameter than the bore 22 of the supply pipe 10 or the bore 23 of the torch 18. Fixed to the upwardly projecting portion 19 of the torch 18 is a gear 70 75 24 adapted to mesh with the gear 15 of the operating rod 13.

The method of application of my device to a gas stove and the operation thereof is 80 as follows: The main supply pipe 9 of a gas stove is tapped and a T 26 inserted at about its central portion. The screw-threaded end 25 of the supply pipe 10 is screwed into this T. The supply pipe 10 is then connected by 85 this means with the main supply pipe of the stove and in such a manner that my entire device is located beneath the top grating 27 of the stove 4 so that the end 20 of the torch 18 will swing over the burners 5, 6, 7 and 8 90 of the stove and under said top grating. Being attached in this manner the entire device is out of the way. The handle 14 projects a slight distance beyond the front edge of said stove and is in such a position that 95 it can be easily operated. The end 20 of the torch 18 is kept constantly lighted. At this point I wish to call particular attention to the bore 21 of the connecting pipe 17 which is made very small in diameter, much smaller 100 in fact than either the bore 22 of the supply pipe 10 or the bore 23 of the torch 18. The bore 22 of the supply pipe 10 may be of any suitable diameter, even as large as the diameter of the bore of the main supply pipe 105 9. The bore 23 of the torch 18 is preferably of a smaller diameter than that of the main supply pipe 9 but is considerably larger than the bore 21 of the connecting pipe 17. Because of this construction it is possible to 110 allow the gas to come full pressure at all times through the supply pipe 10. Owing to

the very small diameter of the bore 21 only a small amount of gas can pass therethrough. This expands in the comparatively larger bore 23 of the torch 18 and at 5 its outer end burns in the form of a medium size or small flame and without any "blowing" or pressure, thus it is possible to use a very small amount of gas and yet keep the device constantly lighted. It has been found 10 in experimenting that the amount of gas used is extremely slight.

In operation when it is desired to light one or more of the burners 5, 6, 7 and 8 of the stove 4 the torch 18 is revolved in the 15 path indicated by the dot and dash circle A in Fig. 1 by turning the handle 14 until it comes over the burner which it is desired to light. The cock of such burner is opened and the burner instantly lights. Any number 20 of burners can be successively lighted in the same manner.

This invention is particularly valuable in employments where a gas stove is constantly used and where the different burners 25 are being constantly extinguished and relighted, such for instance as in candy factories. In this and other cases it is much more advantageous to use my appliance than to constantly waste matches and more 30 particularly waste the time of employees in procuring and lighting the matches and thus the burners.

It has the further advantage of making 35 the use of a gas stove more safe for the reason that there can be no such explosions as sometimes occur when the gas is turned on and then a match cannot be found and lighted for several seconds; furthermore, it obviates the necessity of having a large 40 supply of matches constantly on hand.

Having thus described my invention what I claim and desire to secure by Letters Patent is:

1. A gas lighting device comprising in 45 combination a horizontally disposed supply pipe, a vertically disposed pipe connected therewith, a torch comprising a horizontal portion and a vertical portion, the vertical portion being connected with and rotatably 50 mounted on said connecting pipe and the bore of said connecting pipe being smaller in diameter than the bore of either said supply pipe or said torch, and means to rotate said torch.

55 2. A gas lighting device comprising in

combination a horizontally disposed supply pipe, a torch comprising a vertically disposed portion and a horizontally disposed portion, the vertically disposed portion being connected with and mounted on said 60 supply pipe, a plurality of brackets fixed to said supply pipe, an operating rod rotatably mounted in said brackets and means to connect said operating rod with said torch whereby said torch may be revolved. 65

3. A gas lighting device comprising in combination a horizontally disposed supply pipe, a vertically disposed pipe connected therewith, a torch comprising a horizontal portion and a vertical portion, the vertical 70 portion being connected with and rotatably mounted on said connecting pipe, and means to rotate said torch.

4. A gas lighting device comprising in combination a horizontally disposed supply pipe, a vertically disposed pipe connected therewith, a torch comprising a horizontal portion and a vertical portion, the vertical portion being connected with and rotatably 75 mounted on said connecting pipe, the bore of said connecting pipe being smaller in diameter than the bore of either said supply pipe or said torch, a gear fixed to said torch, a plurality of brackets fixed to said supply pipe, an operating rod rotatably mounted in 80 said brackets, and a gear fixed to said operating rod and adapted to mesh with said gear fixed to said torch, whereby said torch 85 may be rotated.

5. In a gas range provided with a main 90 supply pipe a gas lighting device comprising in combination a horizontally disposed supply pipe directly connected with said main supply pipe, a vertically disposed pipe connected with said last mentioned pipe, a 95 torch comprising a horizontal portion and a vertical portion, the vertical portion being connected with and rotatably mounted on said connecting pipe and the bore of said connecting pipe being smaller in diameter 100 than the bore of either said supply pipe or said torch and means to rotate said torch.

In testimony whereof I have hereunto set my hand in presence of two subscribing witnesses.

THOMAS S. NEWMAN.
